UNITED STATES PATENT OFFICE.

MORIZ WEINRICH, OF YONKERS, NEW YORK.

PROCESS OF PURIFYING MASSE-CUITE OR SYRUP.

No. 822,171.

Specification of Letters Patent.

Patented May 29, 1908.

Application filed May 22, 1905. Serial No. 261,587.

To all whom it may concern:

Be it known that I, MORIZ WEINRICH, a citizen of the United States, residing at Yonkers, in the county of Westchester and State 5 of New York, have invented new and useful Improvements in Processes of Purifying Masse-Cuite or Syrup, of which the following is a specification.

My invention relates to a new and useful process of purifying masse-cuite or syrups; and it consists of the steps and series of steps constituting the novel process, which I will hereinafter describe and claim.

In the accompanying drawing I illustrate 15 one form of apparatus by means of which my process may be successfully worked.

In a prior patent, No. 711,603, granted to me October 21, 1902, there is disclosed a process for purifying and preserving raw sugar 20 by means of powdered lime before it undergoes the ordinary refining process and wherein was secured a more energetic purification, and when applied to the working of beet-sugar the elimination of the objectionable 25 smell and taste which become concentrated in the residual molasses. I have found that substantially the same system is applicable and can be used to great advantage to masse-cuite, a mixture of sugar crystals and syrup 30 or molasses. The process can also be used with the various kinds of centrifugal runnings, which are the syrups or molasses flowing from the centrifugal machines as commonly used in the sugar industry.

35 In working my improved process I have succeeded in removing from seventy to ninety per cent. of the total color and from forty to sixty per cent. of the total impurities present in the masse-cuite or syrup. In 40 addition when treating masse-cuite or syrups derived from cane-sugar I have succeeded in preserving all the fruit-sugar or glucose present without forming any lime salts, which latter are so detrimental to crystallization and to the taste and flavor of the 45 residual syrup.

To make my present invention fully understood and appreciated, I have disclosed in the drawing a form of apparatus well suited 50 for my purpose; but the precise character of the mechanical features therein shown are immaterial, as other forms of apparatus may be used and come within the scope of my invention.

55 To attain the results before alluded to, I

prefer to follow the methods which I will now describe, having reference to the aforesaid drawing.

The masse-cuite or the runnings to be treated are mixed intimately and uniformly 60 with a certain percentage of burnt lime (CaO) in a finely-divided or powdered state. Therefore I employ a closed vessel A of appropriate size and construction, preferably cylindrical, having within it a suitable stirring 65 mechanism which may include the arms b, fixed to a revolvably-mounted shaft b' and operating in conjunction with other and stationary arms a, fixed to the inside of the vessel. Connecting with one end of the vessel 70 are two inlets, through one of which, d, the masse-cuite or runnings from the centrifugal are introduced in measured quantities and through the other, d', the lime-powder is admitted, also in measured charges or quanti- 75 ties. The vertical shaft has means, as a pulley, through which power is applied to rotate the stirrer-arms b, and by maintaining the cylinder or vessel A substantially full an intimate admixture of masse-cuite or centrifugal runnings and lime is effected. In the op- 80 posite or lower end of the cylinder or vessel A is a gate-controlled outlet e, through which the mixed masse-cuite is allowed to run continu- 85 ously into a second mixer B of well-known form, having a revoluble stirrer B' and having delivery-pipes c e' with gates controlling the discharge therefrom. This second mixer B in practice should have suf- 90 ficient capacity to allow the mixture to be re- 95 tained therein, say, from twenty (20) to thirty (30) minutes before receiving its fur- ther treatment to enable the lime in the mix- ture to act thoroughly on the impurities and coloring-matter under continuous stirring. When the centrifugal runnings or molasses of any kind have been thus intimately mixed 100 with the lime, they are allowed to run from the second mixer through the gated outlets e' into a tank C, having an internal stirrer of appropriate character—say like the stirring devices previously described for the cylinder A. In the tank C the runnings are diluted with water to about thirty Brix., and from the tank C the material is pumped into car- 105 bonation-tanks and therein carbonated to 0.1 per cent. alkalinity and filtered through filter-presses. The material is then carbon- ated for a second time (after adding about ten per cent. of the amount of lime used in 110

the beginning) to neutrality or near to neutrality and then filtered again, whereupon the purification is completed.

If desired, instead of carbonic-acid gas phosphoric acid or sulfurous acid may be used; but carbonic-acid gas is to be preferred, because it is much cheaper and filtration thereby as commonly followed is more readily effected. In my working of this process 10 I have obtained good results by carbonating at the second carbonation only to 0.1 per cent. alkalinity and then neutralizing by means of dilute phosphoric acid.

When treating masse-cuite or a mixture of raw sugar and syrup the treated mass is purged in a centrifugal D, so situated that it will receive the masse-cuite from the mixer B.

A portion of the lime added to the mixture has formed with a part of the sugar in solution 20 a sucrate of lime in the form of granular particles, which particles partly adhere to the sugar crystals and partly float in the surrounding syrup. These particles are retained in the centrifugal D, together with the sugar, and increase the yield very materially. 25 On the other hand, when dissolving such sugars it is necessary to neutralize the lime in the sucrate in the manner before pointed out. When using instead of powdered 30 caustic lime or powdered dry slaked lime, no such granular sucrate of lime is formed, and by washing the remaining sugar in the centrifugal by the water or steam methods usually adopted in the industry the first 35 sugar will be neutral or only faintly alkaline. The runnings from the centrifugal are, however, strongly alkaline and have to be diluted and carbonated in a manner similar to that before pointed out.

40 The amount of lime to be used in my process varies in proportion to the amount of impurities present. Generally I use one (1) part of finely-powdered caustic lime (CaO) to one and one-half (1½) parts of impurities, not counting fruit-sugar or glucose as 45 impurity, so that if, for instance, beet-sugar runnings or syrups consist of sixty-five (65) per cent. sugar, fifteen (15) per cent. impurities, and twenty (20) per cent. 50 water I add ten (10) per cent. of lime-powder, and if cane-sugar runnings or syrup consist of fifty-five (55) per cent. sugar, ten (10) per cent. fruit-sugar, and fifteen per cent. impurities, and twenty (20) per cent. 55 water I add likewise ten (10) per cent. of lime-powder.

60 While I prefer to employ caustic lime in my process, I do not wish to be understood as limiting the process to this substance, 60 because I may substitute for the caustic lime a fine powder of dry slaked lime. However, I prefer to use the caustic lime, because it is more energetic in its action on the impurities and coloring-matter than is 65 hydrated lime.

The syrup or molasses in the masse-cuite or the runnings to be treated shall have a density of at least 36° Baumé, preferably 70 40° to 42° Baumé, as I have found that the lime acts with more energy on color and impurities when the latter are in a concentrated state, on which principle and observation my hereinbefore-mentioned process and my present process are based. When applying, for instance, milk of lime to a thin sugar solution and carbonating at the temperatures generally employed, only about half as 75 much color and impurities will be removed and considerable fruit-sugar will be destroyed and lime salts formed than when applying powdered caustic lime to a concentrated solution of the same purity and carbonating it at the temperatures substantially as hereinbefore pointed out.

80 The various temperatures which I prefer to employ after many experiments with my process at its various stages and for the different kinds of material to be treated are of prime importance and constitute an essential feature of my invention.

90 When working masse-cuite or runnings from cane-sugar, it should be warmed up before mixing with the lime-powder to 43° to 45° centigrade. After adding the lime the temperature of the mass increases by the action of the lime to about 50° centigrade. A temperature substantially in excess of 50° centigrade 95 should be avoided, owing to the fact that such increased temperature would result in the destruction of the fruit-sugar in the mass and the formation of lime salts would set in. The temperature during the first and second carbonation should be maintained between 35° and 100 under 45° centigrade for the same reason.

105 When the first carbonation is completed, the temperature can be safely raised to 55° to 60° centigrade to insure a satisfactory filtration, and when the second carbonation is finished the temperature may be increased to 95° to 100° centigrade. In this 110 manner all the fruit-sugar or glucose present will remain unimpaired and there will be an absence of the objectionable lime salts.

115 When working masse-cuite or runnings from beet-sugar, which generally contain no glucose, the temperature before mixing should be 50° to 55° centigrade, which will increase 5° centigrade by the action of the lime. If the temperature before mixing is brought above 60° centigrade, the caustic 120 lime will act too violently and may cause the formation of caramel.

125 The temperature during and after the first carbonation of beet-sugar solutions can be safely maintained at 70° to 80° centigrade and the temperature during the second carbonation at or about the same; but that temperature is increased when carbonation is completed, and before filtration to 95° to 100° centigrade.

My process can be followed to great advantage not alone in refineries, but also in beet and cane sugar factories. The said factories when treating their runnings from their first product by this process are enabled to purify them to such a degree that a large part of these runnings from the first product can be taken back and boiled along with the first product, thus increasing their yield in sugar and materially diminishing their output of molasses.

Having thus described my invention, what I claim as new, and desire to secure by Letters Patent, is—

15 1. The process of purifying masse-cuite or impure sugar solutions which consists, essentially, in bringing the solution to a density of at least 36° Baumé; warming said solution to about 43° to 45° centigrade; mixing 20 intimately and substantially uniformly therewith an amount of dry, finely-powdered, caustic lime equal to about one-half to two-thirds of the impurities present; and carbonating at temperatures below 45° centigrade.

25 2. The process of purifying masse-cuite or impure sugar solutions which consists essentially in bringing the solution to a den-

sity of about 42° Baumé; warming to a temperature at which the lime will decompose 30 and combine with the impurities present, but below that which will destroy the fruit-sugar present or form caramel; mixing intimately and substantially uniformly therewith a quantity of dry, finely-powdered, 35 caustic lime equal to one-half, to two-thirds of the impurities present; and carbonating the mixture at temperatures as defined above.

3. The process of purifying masse-cuite or impure sugar solutions which consists, essentially, in bringing the solution to a density of at least 36° Baumé; warming said solution to about 43° to 45° centigrade; mixing intimately and substantially uniformly therewith an amount of dry, finely-powdered 40 lime, equal to about one-half to two-thirds 45 of the impurities present; and carbonating at temperatures below 45° centigrade.

In testimony whereof I have hereunto set my hand in presence of two subscribing witnesses.

MORIZ WEINRICH.
